(No Model.)

E. P. GLEASON.
AUTOMATIC FIRE EXTINGUISHER.

No. 416,779.

Patented Dec. 10, 1889.

ATTORNEY

UNITED STATES PATENT OFFICE.

ELLIOTT P. GLEASON, OF NEW YORK, N. Y.

AUTOMATIC FIRE-EXTINGUISHER.

SPECIFICATION forming part of Letters Patent No. 416,779, dated December 10, 1889.

Application filed October 7, 1887. Renewed May 13, 1889. Serial No. 310,687. (No model.)

To all whom it may concern:

Be it known that I, ELLIOTT P. GLEASON, a citizen of the United States of America, and a resident of the city, county, and State of 5 New York, have invented certain new and useful Improvements in Automatic Fire-Extinguishers, of which the following is a specification.

My invention relates to fire-extinguishers 10 of that class known as "sprinklers," my objects being the production not only of a simple and reliable extinguisher, the operation of which may be started and stopped by hand or which will start automatically, but also one 15 which will stop automatically after a limited time and remain so if the fire has been extinguished, or if the fire continues will start in operation again; also, one which, when a fire occurs, 20 will cause an alarm at any place de- sired, as the office or the dwelling of the superintendant or proprietor.

My invention consists in the construction, arrangement, and combination of parts and the combination of several devices whereby 25 the objects before stated are attained, as will more fully appear in the following specification, of which the accompanying drawings form part, in which—

Figure 1 shows a side elevation of the fire-extinguishing device, a portion of the discharge-nozzle and the distributor being shown in central section, the weighted lever in elevated position, with the plug-valve closed and the electric connection open, and also a side 35 elevation of a clock mechanism and a view, partly sectional, of the weight support and releasing device. Fig. 2 is a cross-section of the discharge-nozzle and plug-valve, showing construction of parts, the weighted lever connected and in fallen position, with the plug-valve open and electric connection closed. Fig. 3 is a side elevation of a modified form 40 of extinguisher with the plug-valve separate from the discharge-nozzle. Fig. 4 is a front view of a portion of the clock mechanism and the weight supporting and releasing device, also showing side view of the magnet-armature and connections.

Like letters and figures are used to designate like parts on all the figures.

A is an ordinary service-pipe, to a T or el-

bow a of which is secured a discharge-nozzle B, which is provided with a distributor for the extinguishing-fluid, of any suitable construction. I prefer a disk b, suspended on a central shaft b' a short distance below the orifice of the discharge-nozzle B, as shown at Fig. 1. Entering through an annular flange 1 on one of the sides of this nozzle B is a plug C, the inner end of which is adapted to serve 60 as a valve and to close a port 2, the margin of which is adapted to serve for its seat, to and from which it is moved by a quarter-turn by means of the steep-pitch screw-thread on its periphery engaging a corresponding screw-thread within the annular flange 1. To the outer end of this plug C a weighted lever D is secured. The free end of this lever D carries a weight d, which may be rigidly secured to it or may be swung from it, as preferred. A 65 grooved pulley E is connected to this lever by its side plates e e, which are soldered to it with a solder that will fuse at low temperature. A cord or wire F passes between the plates e e under the pulley E, one end of which is secured to an eyelet disk or plate f, which in turn is soldered onto another eyelet disk or plate f' with solder that will fuse at 70 low temperature, and this plate f' is secured to a suitable fastening f'', located at a point 75 above (and preferably behind) the fulcrum of the lever D and stop-cock C, so as to have the length of the cord or wire between the pulley E and the plate f enough to allow the lever D to drop to a vertical position. The 80 plate f'' is secured to the fastening f'' by a loop or tie G, of cord or tape, which has the properties of a fuse or is made of explosive or combustible material. This cord or tape G is made of such length that whenever de- 85 sired its free end or portion G' will reach and coil around or about the place, machine, or material where fire may occur and serve as a fire-transmitter, rapidly transmitting fire, when it becomes ignited, to the loop G. 90

The cord or wire F, extending from the plate f', passes under the pulley E on the lever D, then upward over the pulley E', which is positioned at a point about vertically over the pulley E when the lever D is in horizontal position. The cord or wire F then passes on over suitable pulleys to any desired place, 95 100

terminating in connection to a ring f''' or any other suitable hand-grip and catching device adapted to hook to the weight H, hereinafter described. In the course of this cord 5 or wire F a spiral spring f^4 is intervened and serves to impart an elastic function to the action of the cord or wire F, thus preventing shock or jar from any sudden strain.

A weight H, heavier than the weight d on 10 the free end of the lever D, is suspended upon a tripping-lever I, which is pivoted to the lugs k k' of a supporting-plate K, which is securely fastened in position on a wall or post at a proper distance above the floor to 15 allow room for the weight H to fall a distance equal to the length of the wire or cord F between the plate f' and the pulley E when the lever D is in the horizontal position. This lever I is formed with hook-shaped prongs i i' 20 on its lower end, which are adapted to catch and hold to the ring-bolt or T-handle of the weight H. Its other end i' extends upward behind a semi-cylindrical cam L, which serves to lock it in position. This cam L is securely 25 mounted in a lug or bearing k' , projecting from the plate K, in which it is adapted to revolve, and it is connected to a device of clock mechanism M by means of the shaft l. This clock mechanism may be such as is used 30 in an alarm-clock, and capable of being set for motion to such time limit as may be desired. Attached to this clock mechanism are an electro-magnet N and armature n, which are positioned close to the fan m of the 35 clock mechanism and in such relation thereto that whenever the armature n is not drawn against the electro-magnet N a lug or projection from it will intercept a wing of the fan m, and thus prevent motion of the clock 40 machinery until such times as the armature n is drawn against the electro-magnet N, when the machinery will be released and free to run and revolve the connecting-shaft l and cam L until it comes to the position as shown 45 by the dotted line at L, when the lever I will be released and will swivel on its pivot and release the weight H.

Wires o o connect the electro-magnet N with a battery S and a switch-piece P, which 50 is secured to the stop-cock by an insulating ring g, and which is adapted for contact with and electrical connections with the heel end d' of the lever D, which, it will be observed, is also adapted for such connection. It will 55 also be observed that the lever D may be actuated by hand either to open or close the cock and start or stop the flow of extinguishing-fluid simply by unhooking the ring or grip from the weight H. Thereby any person 60 present, when a fire occurs, may start the extinguisher in operation or stop it when the fire is extinguished. A circuit of wire o o is made from the pipes A and the battery S, which is adapted to connect with an ordinary 65 electric alarm located in the office or other place desirable, thus completing what is involved in this invention.

The clock mechanism being wound up and set to a time limit, and all the parts in the position as shown by Figs. 1 and 4, my invention is ready for operation, which is as follows: Should a fire occur near by where it is located, it will be communicated to the fire-transmitting tape or cord G', which in turn will rapidly transmit it to the loop G, which 70 will instantly burn and sever, or the heat generated by the fire will fuse the solder holding the plates f and f' together, and they will separate. In either case the cord or wire F will drop, and the lever D and weight d, being released from the support of the cord or wire F, will also drop, thus turning the plug-valve C and permitting the extinguishing-fluid to flow through the pipes and nozzle 80 and to be thoroughly distributed by the distributor b. At the same time the heel end d' of the lever D is swung in contact with the switch-piece P and connection made for the electric current supplied by the battery S, which magnetizes the electro-magnet N and 85 draws the armature n against it and away from the fan m, thus leaving the clock machinery free to run the limit of time for which it has been set, thereby revolving the cam L to the position shown by the dotted lines at 90 L, whereupon the lever I, being released, swivels and unhooks the weight H, which falls to the floor, drawing with it the cord or wire F, and through it drawing the weighted lever D back to its horizontal position, thus turning 95 the plug-valve C and stopping the flow of fluid. It should be observed that the plate f, to which the cord or wire F is firmly attached, is too large to pass between the plates e e of the pulley E, and that it will catch there, 100 thereby serving as the needed attachment of the said wire to the lever D. If after the above action has taken place the fire should still continue, then the solder holding these plates e e to the lever D will be fused by the 105 heat generated, and the lever D, again released, will fall, and, as before stated, the plug-valve be opened and the extinguishing-fluid permitted to flow. It will be noted, however, that the solder joining these plates and 110 the lever will not fuse at so low a temperature as that joining the plates f and f', because of the greater amount of metal to be heated. At the same time that the electrical connection is made between the heel d' of the lever D and the switch-piece P electric force from the battery S will be transmitted 115 through the wires o o to any connected alarm in the office or other place, which will continue to sound until the connection is broken 120 by the return of the lever D to the horizontal 125 position.

Having thus described my invention, what I claim as new, and desire to secure by Letters Patent, is—

1. In automatic fire-extinguishers, a nozzle provided with a distributor for the extinguishing-fluid, a plug-valve having a screw-thread on its periphery, which engages in and enters

through an internally-screw-threaded annular flange opened in the side of the said nozzle and is adapted to close a port within the same, and an internally-threaded annular flange attached to the side of said nozzle and adapted to receive said plug-valve, in combination with a lever secured to the outer end of said plug-valve and suitable means for operating the same, in the manner and for the purpose specified.

2. The combination, in an automatic fire-extinguisher having a system of pipes and distributing devices with valves which are operated by weights, of a trip-lever, as I, its supporting-plate, as K, locking-cam, as L, weight, as H, wire or cord, as F, and clock mechanism, as M, arranged in the manner and for the purpose described.

3. In automatic fire-extinguishers having a valve controlling the flow of an extinguishing-fluid, which is actuated by a weighted lever, the combination of a weighted lever connected with said valve, which is adapted to close an electric circuit by contact with a switch-piece, as P, with a switch-piece, as P, and an electric circuit consisting of conducting-wires, a battery, and the pipes of the extinguishing system, a magnet adapted to release the stop device of a clock mechanism, and thus effect its starting in motion, a clock mechanism adapted to effect the release of a

counter-weight, as H, a counter-weight, as H, and a wire, as F, connecting the same to the said weighted lever, substantially in the manner and for the purpose described.

4. The combination, in an automatic fire-extinguisher consisting of a system of pipes, discharge-nozzle, and valve actuated by a weighted lever, of a weighted lever, a counter-weight of greater gravity than said lever, and which is normally supported in elevated position by means of a device adapted to trip and release it, a cord, chain, or wire having one or more joints which will fuse in a comparatively low temperature, and which connects said weighted lever to said counter-weight, so as to serve as the means of supporting said weighted lever in elevated position, a tripping device, substantially as described, for supporting said counter-weight, which is adapted to be released by the action of a clock mechanism, and a clock mechanism adapted by suitable means to be started in motion when said weighted lever falls.

In testimony that I claim the foregoing as my invention I have signed my name, in presence of two witnesses, this 30th day of September, 1887.

ELLIOTT P. GLEASON.
